[57] CLAIM

The ornamental design for a telephone equipment cabinet chassis, as shown and described.

DESCRIPTION

FIG. 1 is a left front perspective view of a telephone equipment cabinet chassis showing my design;
FIG. 2 is a top plan view of the telephone equipment cabinet chassis of FIG. 1;
FIG. 3 is a right side, the side opposite to that shown in FIG. 1, elevation view thereof;
FIG. 4 is a rear elevation view thereof; and
FIG. 5 is a bottom plan view thereof.
